WILFORD H. TEETER, OF DAYTON, OHIO, ASSIGNOR, BY MESNE ASSIGNMENTS, TO
DELCO PRODUCTS CORPORATION, OF DAYTON, OHIO, A CORPORATION OF DELAWARE

CHARGE FORMING DEVICE

Application filed September 25, 1928. Serial No. 308,242.

This invention relates to charge forming devices for internal combustion engines and more particularly to the type of charge forming device which comprises a plurality of primary fuel mixing chambers, one for each intake port of the engine and cooperating respectively with a plurality of secondary mixing chambers located adjacent the engine intake ports and receiving fuel air mixture from pipes connected with the primary carburetors and receiving air when required through branches of an air manifold having a single air inlet for supplying air to all the secondary mixing chambers. A common fuel reservoir supplies liquid fuel to all the primary mixing chambers.

Examples of charge forming devices of this character are disclosed in the copending applications of Wilford H. Teeter, Serial No. 221,372, filed September 22, 1927, which matured into Patent No. 1,819,526 and Fred E. Aseltine and Wilford H. Teeter, Serial No. 221,371, filed on the same date, which matured into Patent No. 1,819,495.

In the devices disclosed in the above applications and in other earlier forms of this type of charge forming device, fuel is lifted in a solid column from the float bowl to the primary mixing chambers. In these earlier devices this distance is from two to three inches and in order to lift the fuel through such a distance a perceptible degree of partial vacuum must be created in the primary mixture passages before the fuel begins to flow at all and the air valve spring must be of such strength as to maintain such a degree of vacuum in the said mixture passages during idling or operation of the engine at very low speed under load. With an air valve spring of this strength the suction in the primary mixture passages builds up so rapidly as the engine speed increases that at higher engine speeds the suction in the primary mixture passages is so great that too large a quantity of fuel is drawn from the

nozzles to form a mixture of proper proportions, the mixture being too rich to most satisfactorily operate the engine unless means be provided to prevent the action described.

It is, therefore, the principal object of the present invention to provide a charge forming device having improved means for supplying fuel to the mixing chamber which is effective to supply the correct amount of fuel under all operating conditions to form a mixture of the desired proportions. More specifically, it is an object of the present invention to provide means for supplying fuel to the mixing chamber which eliminates the necessity of lifting the fuel while in liquid form through any material distance.

According to the present invention these objects are accomplished by the provision of fuel jets located at substantially the same level as the level of fuel in the fuel bowl, means for conducting air past said jets to form an emulsion of fuel and air at said jets, and means for conveying the emulsion to the primary mixing chambers which are located a substantial distance above the fuel bowl and in which the aforementioned emulsion is mixed with additional air to form the primary mixture which is conducted to the secondary mixing chambers in the manner described in the earlier applications above referred to. By provision of this construction fuel is carried to the primary mixture passages when a very slight subatmospheric pressure is maintained therein and a light enough spring may be employed on the air valve to insure the formation of a mixture of desired proportions throughout the entire speed range of the engine.

Further objects and advantages of the present invention will be apparent from the following description, reference being had to the accompanying drawings wherein a preferred embodiment of one form of the present invention is clearly shown.

In the drawings:

Fig. 1 is a plan view of a charge forming device constructed in accordance with the present invention and attached to the cylinder head, a part of which is shown in section.

Fig. 2 is a side elevation of the carburetor unit seen from the right in Fig. 1.

Fig. 3 is a fragmentary front elevation of the device.

Fig. 4 is a vertical section on the line 4—4 of Fig. 1.

Fig. 5 is a vertical section on the line 5—5 of Fig. 4.

The device disclosed comprises a main air manifold 10 having three outlet branches 11, 12, and 13, the middle branch 12 being shown in section in Fig. 4. Each of these branches communicates with one of the intake ports 14 of a multicylinder engine. These outlet branches are each provided with an attaching flange 16 for securing the manifold to the block in the usual manner. Adjacent the inlet of the manifold is provided a flange 18 to which the main carburetor unit is adapted to be attached, as shown in Fig. 1.

The carburetor unit comprises a main housing 20 having an attaching flange 22 adapted to be secured to flange 18 by screws 24. An air inlet horn 26 is secured in position to register with an opening in the upper wall of the housing 20 in any suitable way. A casting 28 having certain fuel and air passages, hereinafter more fully described, formed therein is secured by screws to the bottom of the housing 20, and a sheet metal fuel bowl 30 is held tight against a shoulder 32, formed on a skirt 34 depending from the housing 20, by means of a nut 36 screwed on the reduced lower end 38 of the hollow post 40 forming part of the casting 28, a gasket 42 being provided between the bowl and a flange 44 on said post to prevent leakage. Fuel is conducted from a main source of supply to the fuel bowl through a conduit not shown herein, and the flow of fuel to the bowl is controlled by a float 45 operating in the usual manner to maintain a substantially constant level of fuel therein.

The casting 28 has a chamber 46 formed in the upper part of said casting and a passage 48 formed in the depending post 40 communicates with the said chamber and with the atmosphere. Mounted within the chamber 46 are three fuel nozzles 50 which are screwed into a horizontal tubular portion 52 of the casting 28 which extends across the chamber 46 and in which is bored the horizontal fuel passage 54 which supplies fuel to all of said nozzles. The fuel passage 54 connects at one end with a vertical fuel passage 56 into the lower end of which is screwed a metering plug 58 which regulates the flow of fuel to the nozzles 50. The upper ends of the fuel nozzles are just above the

level of fuel maintained in the fuel bowl so that a very slight partial vacuum at the nozzles will effect a flow of fuel therefrom. Each fuel nozzle projects into a small Venturi tube 60, each of said tubes being screwed into the bottom wall of the main housing 20 and terminating flush with the surface of one of the primary mixture passages 62, as indicated in Figs. 4 and 5. The outlet end of each fuel nozzle is located at the point of greatest suction in its associated Venturi tube, and by means of this construction, a relatively low suction may be maintained in the primary mixture passages 62 while a somewhat higher suction is maintained at the fuel nozzles, the suction in said passages being increased by the Venturi action at the nozzles. Therefore, the spring closing the air valve, as hereinafter more fully described, may be of so little strength that the pressure in the primary mixture passages at idling or operation at very low speed while under load is scarcely less than atmospheric, yet the pressure at the nozzles is sufficiently less than atmospheric pressure to effect a sufficient flow of fuel from the nozzles, this fuel being immediately mixed with air entering through the passage 48, and the emulsion of fuel and air thus formed is light enough to be drawn into the primary mixture passages by the slight sub-atmospheric pressure therein, under any operating condition. Of course, on increase of speed the suction in the primary mixture passages is increased, resulting in increase of suction at the nozzles 50, but because of the provision of the relatively weak spring holding the air valve closed, the increase in suction in the said mixture passage is very little even at relatively high speeds and the increase at the nozzles is insufficient to produce sufficient increase in fuel flow to enrich the mixture as in earlier forms of this device. Moreover, by varying the size of the Venturi tubes 60, the suction at the jets 50 and the flow of fuel therefrom may be controlled substantially as desired.

The primary mixture passages 62 are parallel to each other and close together, as indicated in Fig. 5, and when the carburetor unit is attached to the manifold, these passages register with conduits which convey the primary mixture to the secondary mixing chambers. These conduits are of substantially the same construction as disclosed in the earlier applications above referred to, and comprise pipes 61 communicating with the two outer passages 62 and extending to the branches 11 and 13 of the manifold where they register with tubes 63 secured in the said manifold branches. The middle mixture passage communicates directly with a tube 65 fixed in the outlet branch 12 of the manifold, as shown in Fig. 4, which conveys the primary mixture to the secondary mixing chamber in that particular branch of the

manifold. A single throttle 64, which extends across all of the primary mixture passages, controls the flow therethrough and is provided with grooves 66 which register with 5 said mixture passages. This throttle is operated by means disclosed in the above earlier applications and which forms no part of the present invention.

All of the air entering the carburetor except that entering through the passage 48 flows through the air horn 26 controlled by a main air valve 70, normally held against a seat 72 by a spring 74 received between the valve and a flange 76 projecting from a sleeve 15 78 slidably mounted on a stationary guide sleeve 80, fixed in the housing 20, and serving as a guide sleeve for the stem 82 to which the air valve is secured.

When it is desired to choke the carburetor 20 to start the engine, the flange 76 is adapted to be lifted by means of an arm 77 and other connections, as described in the above applications, until the upper end of sleeve 78 engages the valve to hold it against its seat. 25 Sufficient air to carry the starting fuel from the nozzles to the engine intake ports is admitted through the passage 48 hereinbefore described.

The valve 70 admits air to a main air chamber 30 88 which communicates directly with the primary mixture passages 62 and also with a secondary air passage 90 which is adapted to connect with the inlet of the manifold 10 to supply air to all the secondary mixing 35 chambers. A manually operable throttle 92 secured to a shaft 94 controls the flow of air through the passage 90 and is operated by the same operating connections as is the primary throttle 64, these connections comprising 40 an operating arm 98 connected to a spindle 100 projecting from the primary throttle and connected by a lost motion linkage 102 to an arm 104 secured by screw 106 to the shaft 94 of the air throttle 92. The construction 45 of the lost motion linkage is such that the primary throttle may make a predetermined opening movement independent of the air throttle after which they move together. These operating connections form no part 50 of the present invention and are described in detail in the earlier applications above referred to.

On opening of either or both of the above described throttle valves the suction in the 55 main air chamber 88 is increased and additional air admitted to increase the quantity of mixture supplied to the engine. The opening of the valve must be retarded to some extent, however, to prevent admission of enough 60 air to lean the mixture temporarily. A dash pot is provided to accomplish this result and to prevent fluttering of the air valve, comprising a cylinder 110 and a piston 112 secured to the lower end of the valve stem 82 65 by means of a nut 114 or in any suitable man-

ner. Fuel is admitted through an orifice 116 in the bottom of the cylinder 110 and said orifice is closed by a check valve 118 on downward motion of the piston 112 in the usual way. This dash pot forms no part of the 70 present invention and may be of any conventional construction.

A secondary mixing chamber is associated with each outlet branch of the manifold, these mixing chambers being of identical construction. Each comprises a Venturi tube 120 provided with an external rib 132 which, when the manifold is secured to the engine block, is clamped between shoulders 134 and 136 on the manifold and engine block respectively. Each venturi is so positioned with respect to its associated primary mixture conduit that the point of greatest suction in said Venturi tube is immediately adjacent the outlet end of said primary mixture conduit. The tubes increase the velocity of air flow at the ends of said conduits, insuring at all times a relatively high suction in said conduits.

It will be understood that in general the construction of the device disclosed herein is much the same as that disclosed in the earlier applications above referred to. The novel construction to which the present invention is directed comprises the means for forming 90 an emulsion of fuel and air and conveying this emulsion to the primary mixture passages. It will be obvious that while the device disclosed shows a preferred form of this invention, the novel structure could be embodied in charge forming devices of different construction than that illustrated herein.

It will also be understood that, although no fuel pump or other means for enriching the mixture for acceleration has been shown herein, for the sake of simplicity of disclosure, any well-known means for enriching the mixture may be provided, as for instance either of the forms of fuel pump shown in the earlier applications above referred to.

While the form of embodiment of the present invention as herein disclosed, constitutes a preferred form, it is to be understood that other forms might be adopted, all coming within the scope of the claims which follow.

What is claimed is as follows:

1. A charge forming device for internal combustion engines comprising a secondary mixing chamber, an elongated primary passage having one end opening into said secondary mixing chamber, a throttle in said primary mixing passage near the other end thereof, means for supplying a super-rich mixture of fuel and air to said primary mixing passage under all operating conditions and at a point close to that side of the throttle which is remote from said secondary mixing chamber, means near the first mentioned means for admitting air to said pri- 120 125 130 135

mary mixing passage to dilute said super-rich mixture, said primary mixing passage and the said two means being adapted to deliver a primary mixture of properly combustible proportions to said secondary chamber for all positions of said throttle from the closed position to a predetermined open position thereof, and means controlled by movement of said throttle for admitting air to said secondary mixing chamber.

2. A charge forming device for internal combustion engines comprising a secondary mixing chamber, a primary mixing passage, a throttle in said primary mixing passage, means for supplying a super-rich mixture of fuel and air to said primary mixing passage under all operating conditions, means for admitting air to said primary mixing passage to dilute said super-rich mixture, said primary mixing passage and the said two means being adapted to deliver a primary mixture of properly combustible proportions to said secondary mixing chamber for all positions of said throttle from the closed position to a predetermined open position thereof, and to deliver a super-rich mixture to said secondary mixing chamber for open positions of said throttle beyond said predetermined position, and means controlled by movement of said throttle beyond said predetermined open position for admitting air to said secondary mixing chamber.

3. A charge forming device for internal combustion engines comprising, a secondary mixing chamber, a primary mixture passage, a throttle in said primary mixture passage, said primary mixture passage being adapted to deliver a primary mixture of properly combustible proportions to said secondary mixing chamber at all engine speeds below a predetermined speed, and a super-rich mixture to said secondary mixing chamber at higher speeds than said predetermined speed, means for supplying a super-rich mixture of fuel and air to said primary mixture passage at all speeds, means for admitting air to said last named passage to dilute said super-rich mixture at all speeds, and means controlled by said throttle for admitting air to said secondary mixing chamber at speeds above said predetermined speed to further dilute the super-rich mixture.

4. A charge forming device for internal combustion engines comprising a plurality of mixture passages, a fuel reservoir below said mixture passages, an air supply passage extending through said fuel reservoir and provided with an enlargement therein, a plurality of fuel jets in said enlargement, each of which is adapted to supply fuel for one of said mixture passages, and a plurality of Venturi tubes in said enlargement, each of which surrounds one of said jets and communicates with one of said mixture passages, whereby flow of fuel from all of said jets is

effected and the resulting mixture conveyed to said mixture passages.

5. A charge forming device for internal combustion engines comprising a plurality of primary mixture passages, a plurality of secondary mixing chambers into which said passages deliver, a fuel reservoir below said mixture passages, an air supply passage extending through said reservoir, and provided with an enlargement therein, a plurality of fuel jets in said enlargement, each of which is adapted to supply fuel for one of said mixture passages, means for effecting a flow of fuel from said jets and for conveying the mixture thus formed to said mixture passages, means for supplying additional air to all of said mixture passages to further dilute the mixture supplied thereto and means for supplying air to said secondary mixing chambers.

6. A charge forming device for internal combustion engines comprising a plurality of primary mixture passages, secondary mixing chambers into which said primary mixture passages deliver, a fuel reservoir below said mixture passages, an air supply passage adapted to communicate with all of said mixture passages, a plurality of fuel jets located in said air supply passage at substantially the level of fuel in said reservoir, each of which is adapted to supply fuel to one of said primary mixture passages, means for creating a suction at said jets to effect a flow of fuel therefrom, and means for supplying air to said primary mixture passages and said secondary mixing chambers.

7. A charge forming device for internal combustion engines comprising a fuel reservoir, a plurality of horizontal mixture passages above the fuel reservoir, a vertical air passage extending through the reservoir, a plurality of fuel nozzles in said air passage terminating substantially at the fuel level maintained in the reservoir, and a plurality of Venturi tubes surrounding said fuel nozzles, each is adapted to communicate with said air passage and with one of said mixture passages.

8. A charge forming device for internal combustion engines comprising a plurality of substantially horizontal mixture passages, a fuel reservoir below said mixture passages, a substantially vertical air supply passage extending through said fuel reservoir and provided with an enlargement therein, a plurality of fuel nozzles in the enlargement, each of which is adapted to supply fuel to one of said mixture passages, and a conduit extending from each fuel nozzle to its associated mixing chamber, and having means therein for increasing the air velocity adjacent the nozzle to effect a flow of fuel therefrom.

9. A charge forming device for internal combustion engines comprising a plurality of substantially horizontal mixture passages,

a fuel reservoir below said mixture passages, a substantially vertical air supply passage extending through said fuel reservoir and provided with an enlargement therein, a plurality of fuel nozzles in the enlargement, each of which is adapted to supply fuel to one of said mixture passages, a conduit extending from each fuel nozzle to its associated mixing chamber and having means therein for increasing the air velocity adjacent the nozzle to effect a flow of fuel therefrom, and means for supplying additional air to said mixture passages under all operating conditions to dilute the mixture supplied thereto by said conduits.

10. A charge forming device for internal combustion engines comprising a substantially horizontal primary mixture passage adapted to deliver a primary mixture of fuel and air to a secondary mixing chamber, a fuel reservoir under the mixture passage, means for maintaining the fuel level in said reservoir a substantial distance below the mixture passage, a conduit extending downwardly from the mixture passage through the fuel reservoir and communicating with the atmosphere, a fuel nozzle in said conduit terminating substantially at the fuel level, and means in said conduit for creating a suction at said nozzle to effect a flow of fuel therefrom, said means being effective under all operating conditions to cause sufficient flow of fuel to form a super rich mixture of fuel and air in said conduit.

15. 11. A charge forming device for internal combustion engines comprising a substantially horizontal primary mixture passage adapted to deliver a primary mixture of fuel and air to a secondary mixing chamber, a fuel reservoir under the mixture passage, means for maintaining the fuel level in said reservoir a substantial distance below the mixture passage, a conduit extending downwardly from the mixture passage through the fuel reservoir and communicating with the atmosphere, a fuel nozzle in said conduit terminating substantially at the fuel level, and means in said conduit for creating a suction at said nozzle to effect a flow of fuel therefrom, said means being also operative to convey the fuel mixture to the primary mixture passage.

20. 12. A charge forming device for internal combustion engines comprising a substantially horizontal primary mixture passage adapted to deliver a primary mixture of fuel and air to a secondary mixing chamber, a fuel reservoir under the mixture passage, means for maintaining the fuel level in said reservoir a substantial distance below the mixture passage, a conduit extending downwardly from the mixture passage through the fuel reservoir and communicating with the atmosphere, a fuel nozzle in said conduit terminating substantially at the fuel level, means in said conduit for creating a suction at said

nozzle to effect a flow of fuel therefrom, said means being effective under all operating conditions to form a super rich mixture of fuel and air to be supplied to the primary mixture passage, and means for admitting air under all operating conditions to said primary mixture passage to dilute the super rich mixture therein.

25. In testimony whereof I hereto affix my signature.
